UNITED STATES PATENT OFFICE

FREDRICK G. WAGENER, OF CHICAGO, ILLINOIS

CLAMPING PIN

Application filed July 29, 1929. Serial No. 381,882.

This invention relates to improvements in clamping pins and, more especially, such a pin adapted to be secured to fabric and carrying clamping means for securing thereto another piece or end of material, for example, fabric.

The invention, for example, is well adapted for use in connection with sanitary bandages. It is extremely simple and convenient 10 in use and a great improvement on the common safety pin.

Other features and advantages of my invention will appear more fully as I proceed with my specification.

15 In that form of device embodying the features of my invention shown in the accompanying drawings—

Figure 1 is a view in perspective showing the device in use; Fig. 2 is a view taken as indicated by the line 2 of Fig. 1; Fig. 3 is a view in perspective showing the pin open; Fig. 4 is a view in perspective of a modified form; and Fig. 5 is a view taken as indicated by the line 5 of Fig. 4.

25 As shown in the drawings, 10 indicates an open rectangular frame having pivotally mounted on one end a pin 11 for securing the device itself to a fabric.

The pointed end 11^a of the pin 11 is adapted 30 to be secured in the clasp 12.

Numeral 13 indicates a clamping bar also pivoted to one end of the frame 10. This clamping bar is channel-shaped in cross section and provided with teeth 13^a along the 35 edges. When the pin 11 is secured in fabric, the bar 13 may be swung into clamping position parallel to and straddling the pin 11 to clamp another piece or end of material between the pin 11 and bar 13. The bar 13 may 40 be held in clamping position by a shorter locking bar 14 pivoted to the other end of the frame, also channel-shaped in cross-section, and adapted to be snapped or sprung down over the bar 14, as shown in Fig. 2.

45 The modified form shown in Fig. 4 is the same as the other except that the locking bar 14 is omitted. Instead, the locking bar 113 corresponding to the bar 13 of the preferred 50 form is made somewhat longer and provided at its end with a hole 114 adapted to be

snapped or sprung over the retaining knob 115 to hold the clamping bar in clamping position.

As an example of one use for the device, it is shown in Figs. 1 and 2 as secured or pinned to the tab 15 of a belt 16 and the clamping bar 13 is shown clamped over the end 17 of a sanitary bandage.

While I have shown and described certain embodiments of my invention, it is to be understood that it is capable of many modifications. Changes, therefore in the construction and arrangement may be made without departing from the spirit and scope of my invention as disclosed in the appended claims, in which it is my intention to claim all novelty inherent in my invention as broadly as possible, in view of the prior art.

What I regard as new, and desire to secure by Letters Patent, is:

1. A device of the character described, including; a frame; a securing pin pivotally attached to the frame; a clasp carried by the frame for the end of the securing pin; a clamping bar carried by the frame and adapted to be swung into clamping position adjacent the securing pin to clamp material between the pin and bar; and means for holding the clamping bar in clamping position.

2. A device as claimed in claim 1, in which the clamping bar is channel-shaped in cross-section and adapted to straddle the pin when in clamping position.

3. A device as claimed in claim 1, in which the clamping bar is channel-shaped in cross-section and provided with teeth on its edges and adapted to straddle the pin when in clamping position.

4. A device as claimed in claim 1, in which the clamping bar is adapted to be held in clamping position by a channel-shaped locking bar pivoted to the frame and adapted to be sprung over the clamping bar.

In witness whereof, I have hereunto set my hand, this 19th day of July, 1929.

FREDRICK G. WAGENER.
